TEXTILE PRINTING APPARATUS

Herman A. Smith, Holden, Mass., assignor to Rice Barton Corporation, a corporation of Massachusetts

Application November 9, 1940, Serial No. 365,121

10 Claims. (Cl. 101—178)

This invention relates to textile printing machines, and particularly to the power driving mechanisms which drive the printing rolls and the drying drums or other cooperating apparatus that move the fabric being printed.

A textile printing machine of this type comprises a series of coordinated mechanisms which insure that a roll of fabric may be printed in one or a multiple of colors and then dried by heated drums and passed through other apparatus to a suitable receiver. It is customary to have a back gray cloth travel with the fabric through the printing zone in order to receive any ink that may pass through the fabric or beyond its edges, and this back gray cloth may likewise be dried by means of separate heated drums. The printing is accomplished by means of engraved copper rolls removably mounted on power driven mandrels which press the fabric against a freely rotatable backing cylinder and thereby pull the fabric through the printing zone. When a given printing run has been completed, the printing roll may be removed and another roll of a different diameter may be substituted therefor, or the engraved face of the first roll may be ground away and a new engraving made thereon. In either case, if the printing roll is driven by a constant speed motor, then the rate of movement of the fabric through the printing zone necessarily varies in accordance with the diameter of the roll. The backing cylinder is customarily provided with a wrapping of many layers of cloth or with a rubber covering to form a resilient medium against which the printing pressure is applied. The thickness of that fabric or rubber layer may not be held uniform at the time of its application and it may decrease under the pressure of a long continued printing operation; or the resilient surface of the rubber covering may need to be renewed by grinding away its hardened external layer. Hence, the diameter of the cylinder varies from time to time. Consequently, problems are involved in the attempt to connect mechanically the printing roll or its backing cylinder with the drying drums and other mechanisms if there is to be a proper synchronization of the speeds of the driven parts. On the other hand it is necessary that the printed fabric with its wet ink surface pass directly to the drying drums without contacting with other parts and that the back gray cloth and the fabric should be led from the printing zone with the proper degree of tension. This requires that the printing press and the coordinating drying drums and

other mechanisms have their speeds synchronized without regard to variations in the driving rate of the printer. It, therefore, is desirable to provide a mechanism which operates automatically to insure a full synchronization of the speeds of the fabric and the backing cloth as they pass over their drying drums or other desired apparatus with the speed of the fabric as it is drawn forward by the printing roll in the printing machine.

A primary object of this invention is to overcome such problems and to provide an apparatus of this type in which the speeds of the printing press and another fabric moving mechanism are synchronized so that the fabric may be moved properly for the printing and subsequent operations and it will not be run slack or be pulled out of shape by improper tension.

A further object is to provide a mechanism which automatically synchronizes the speed of the fabric drying drum and the printing press so that the fabric will move under proper tension through both the printing and drying operations irrespective of the primary reference speed applied to one of these moving parts.

A further object of this invention is to synchronize the speeds of the printing press and the mechanism that moves the back gray cloth.

A further object is to provide a speed coordinating apparatus in accordance with which any variation in the speed of the fabric to the printing or any other treatment zone serves automatically to vary the speed of separately driven mechanisms and insure a proper synchronization of the different parts of the apparatus.

A further object is to provide a reference speed unit which moves at the exact speed of the fabric in the printing zone and which is not affected by variations in the size of the printing roll or backing cylinder and which therefore will serve as a reference speed unit for the purpose of coordinating the speeds of the other portions of the apparatus therewith.

A further object is to provide a reference speed unit moving at the rate of the fabric being printed and to control thereby an automatically actuated speed coordinating mechanism which insures that various separately driven motors will drive the fabric or the backing cloth at the same or required speeds in different portions of the entire apparatus. Further objects will be apparent in the following disclosure.

In accordance with this invention, I have provided a textile printing apparatus in which cloth,

whether a fabric to be printed or a back gray cloth, is moved at two remote points by independent motors and associated mechanisms. One motor may move the cloth through the printing zone and the other may drive an independent cloth moving mechanism, such as a drying drum. One motor serves as a master motor and the other is a secondary or controlled motor. In order that the cloth may be driven at the same rate by the two motors, I provide a speed reference unit which moves in an invariable speed ratio relative to the speed of the cloth at a point where it is driven by one of said motors. This unit may be any part of the machine which moves always at the cloth speed, or in a fixed ratio relative thereto, and it is preferably a part which moves at the speed of the cloth in the printing zone. This unit automatically governs a speed control mechanism which causes the secondary motor to move the cloth at the same rate as it is moved by the master motor, irrespective of variations in motor speeds or the texture of the cloth. This synchronization may be effected by various types of apparatus which are either mechanical or electrical, or both.

Referring to the drawings which illustrate a preferred embodiment of this invention:

Fig. 1 is a diagrammatic view of a textile printing apparatus having a printing machine and associated driers for the printed fabric and the back gray cloth, together with coordinating mechanism which insures that the speeds of the various units are synchronized;

Fig. 2 is a fragmentary detail in section and partly in elevation of a differential unit employed in the speed coordinating mechanism;

Fig. 3 is a fragmentary elevation of a modified form of differential unit; and

Fig. 4 is a diagrammatic view of the electrical wiring and speed coordinating mechanisms.

The textile printing apparatus illustrated in the drawings comprises one or more printing rolls 10 engaging the periphery of a backing cylinder 11 and so arranged that the fabric 12, with or without a back gray cloth 14 and/or an endless rubber or other type of blanket 15, may be passed between the printing rolls and the cylinder for the desired printing operation. The backing cylinder is preferably mounted for free rotation about its axis, and it is driven solely by the frictional driving force of the positively rotated printing rolls 10. The printing rolls are driven by an electric motor 16 of suitable type and characteristics and preferably a constant speed direct current motor. The driving force of this motor may be mechanically imparted to the printing rolls by means of a chain belt connection to a driving gear 18 which meshes with a bull gear 19 axially aligned with the cylinder 11; and the latter in turn meshes with the driving gears 20 which are positively connected to rotate the printing rolls.

The fabric to be printed may be derived from the supply roll 22 suitably mounted on standards and arranged to have its fabric withdrawn therefrom as needed by the printer. Similarly, the back gray cloth may be derived from another roll 24, and the fabric and back gray are led over suitable sets of rollers into the printing zone with the back gray cloth 14 arranged between the fabric and the backing cylinder. The rubber blanket lies between these and the cylinder 11. The fabric leaving the printing zone passes around a set of suitably heated drying

drums 26 which are mounted and arranged in accordance with standard practice. The fabric is preferably passed around these drums in such a manner that first one side and then the other 10 is subjected to the drying heat. From these drying drums, the fabric may be then led to other apparatus, such as a swinging folding device 28 which may be driven by a belt 29 connected to a pulley on one of the drums 26. This 15 comprises a swinging arm and power driven rolls adapted to fold the fabric into a suitable receptacle. The details of construction of the drying apparatus and the folder or other apparatus employed may follow any suitable standard construction and need not be described herein.

These fabric drying drums are positively rotated by means of an electric motor 30 of suitable construction and characteristics, which is preferably a direct current motor wound to run 20 at a constant speed that may be varied as desired. This motor is connected by a belt or chain 31 to a pulley on one of the drums, and this in turn is connected through belts or chains 32, 33 and 34 to drive the other drums, as will be understood. The back gray cloth 14 similarly travels from the printing zone to a second set of 25 suitably constructed and arranged drying drums 36 which are connected to rotate together in the direction of cloth movement. The cloth may 30 go back to the printer in an endless travel, or it may pass to a wind up roll 37 or other suitable device. This wind up roll may be mounted on a pair of rolls 38, one of which is suitably driven by a chain connection 39 with a pulley 35 on the last drying drum 36. This set of drying drums may be driven by an independent constant speed direct current electric motor 40 of desired characteristics, which is connected by a chain drive 41 to one of the drums. The other 40 drums may be connected by chain belts to the driven drum to insure their synchronization. The apparatus as so far described may be made in accordance with standard practice and various types of construction and arrangements may 45 be employed.

The primary feature of this invention deals with synchronizing the speeds of the different parts of the apparatus with a selected reference unit. Since the size of the printing roll varies 50 from time to time and the diameter of the backing cylinder itself is variable, I prefer to employ as a reference unit a separate element which receives the speed of the traveling fabric or backing cloth or rubber blanket and is not affected by variable conditions. This reference unit preferably comprises a freely rotatable roll 50 (Fig. 1) mounted on the ends of arms 51 pivotally supported on a part of the framework 52. The roll 50 bears under pressure and preferably 55 that due to gravity against the fabric as it passes over the backing cylinder and through the printing zone. The reference unit is preferably a part of the printing apparatus, since the printing of the fabric is the primary operation to be performed; but under certain circumstances the reference unit may be made a part of the drying drum system for either the fabric or the back gray cloth or it may be any constant speed member in the system. In any case, a primary consideration is that one of the power driven mechanisms shall be a reference unit representing the speed of the fabric or back gray cloth or the endless blanket, to which the speeds of the other mechanisms are referred and with 60 which they are synchronized. The speed ref-

erence unit moves with the fabric in an invariable speed ratio, irrespective of variations in the texture of the driven web or of changes in the operating conditions or of the speed of the master motor which drives the speed reference unit.

Various types of apparatus and arrangements may be employed for synchronizing the motor or motors with this reference unit. The construction illustrated in Fig. 2 of the drawings comprises a differential automatic speed control unit arranged to control the shunt field of the motor to be synchronized. A device of this type comprises two shafts 54 and 55 suitably mounted in bearings in the framework 56. A pulley 57 fixed to the shaft 54 is mechanically connected, as by a belt 58, with a pulley 59 on the reference unit or roller 50. The pulley 60 on the other shaft 55 is connected by a chain belt 61 (Fig. 1) with a pulley 62 which is mounted on the shaft of one of the drying drums 26 or is otherwise mounted to be driven at a speed which is proportional to the speed of the motor 30 that drives the drums. A third shaft 64 mounted between the shafts 54 and 55 carries an ordinary differential gear system of the type found in automobiles, and the two parts of this differential are respectively connected to the two shafts. This comprises a gear 65 pinned to the shaft 54 and meshing with the gear 66 which is keyed to a sleeve 67 mounted for free rotation on the shaft 64. The sleeve 67 carries a bevel gear 68 which meshes with two bevel gears 69 and 70 rotatably mounted on pins 71 and 72 projecting radially from a hub which is pinned to the shaft 64 and revolves therewith. The gears 69 and 70 mesh with a further bevel gear 74, the outwardly projecting hub of which is a sleeve mounted for free rotation on the shaft 64. The sleeve has a gear 75 keyed thereto, and this gear is driven by a gear 77 keyed to the shaft 55 and arranged to rotate therewith. The construction is such that when the shafts 54 and 55 are driven in opposite directions at the same speed, the gears 68 and 74 will rotate equally in opposite directions and the shaft 64 will stand still; but if one of the outside shafts is driven at a higher speed than the other, then the central shaft will be slowly revolved in accordance with that difference in speed. The drives between the outer shafts and the central one have a 1 to 1 ratio, since the motor 30 should drive the drums at the same speed required for passing the fabric 12 through the printing zone. Hence, if the speed of the motor 30 is not synchronized with the speed of the printer motor 16, then the shaft 64 will be revolved slowly in one direction or the other depending on which motor unit is going the faster. I make use of this differential motion to control the speed of the motor whose speed is to be controlled by the reference unit 50.

The intermediate differential shaft 64 may be connected to various types of speed changing mechanism arranged to control the speed of that part of the apparatus which is to be synchronized with the reference unit. I prefer that this be accomplished by means of suitable electrical apparatus which will control the speed of the driving motor for the drying drums. A simple form of an electrical system is diagrammatically shown in Fig. 4, but it will be understood that one skilled in the art may employ other and desired electrical mechanisms for the purpose. In the system there shown, the printer driving motor 16 and the drying drum motor 30 are driven in parallel from a suitable source of electric current.

5 Each motor has a series field S and a shunt field SF. The shunt field of the printer motor 16 is connected across the terminals of the machine through a rheostat R which is adapted to vary the current in the shunt field and thereby vary the speed of the printer motor. Likewise, the shunt field of the motor 30 for driving the drums is connected across the terminals of the motor through a wiring system including a resistance R' adapted for varying the speed of the motor 30. The current flow to the shunt field is also arranged to be controlled through a variable rheostat R₂ having its pivoted contact arm connected to be moved by the intermediate differential shaft 64 of the control apparatus.

10 This is accomplished by means of sprocket 80 (Fig. 2) and a chain 81 connected with a larger sprocket 82. The latter is suitably mounted on a shaft 83 supported on a bearing member 84 and carrying at its opposite end one plate 85 of a friction clutch. The other element 86 of that clutch is keyed on one end of the shaft 87 rotatably mounted on a bearing member 88 and it carries on its other end the pivotal contact arm 90 which sweeps over the contact points 92 of the rheostat R₂ and makes electrical contact therewith. A spring 94 mounted in a recess in the hub of the plate 85 and bearing against the bearing housing 88 holds the friction plates pressed together with a light pressure sufficient to move the rheostat arm but prevent damage in case of an excessive temporary difference in speed. Various other constructional features may be substituted for or combined with the parts here described, as will be understood by one skilled in the art. The rheostat may also be made in accordance with standard construction and need not be here described.

15 The rheostat R₂ has sufficient resistance between the several contact points so as to vary the speed of the motor 30 as required. The rheostat arm 90 and the associated parts are preferably so arranged that this arm will stay in the intermediate position shown in Fig. 4 when the shaft 64 is stationary, and the parts are so connected and arranged that any over speed of the motor 30 relative to the reference unit 50 will cause the arm 90 to move in such a direction as to increase the current flow through the shunt field SF of the motor 30, and thereby slow down the speed of that motor. Similarly, any under speeding of the motor 30 will move the rheostat arm in the opposite direction. Any suitable reduction speed mechanism may be substituted for the gears or pulleys 80 and 82 so as to insure that the rheostat arm movement will take care of the normal maximum range in speed difference of the two motors which are so constructed that the units will run at substantially the same speed.

20 60 Manual control of the clutch of Fig. 2 may be effected by the yoke 93 suitably pivoted on the bearing base 84 which is thrown by the hand lever 96 and held in position by the pawl and ratchet 97. The lever 96 may be connected to open a switch 98 in the printer motor circuit (Fig. 4) when the clutch is disconnected, so that the drying drums may be run after the printer has been stopped.

25 65 70 A modified form of differential unit is shown in Fig. 3. In this construction, the reference roll 50 is connected by a belt 100 with a pulley 101 fixed on the end of a shaft 102 and suitably mounted for rotation in a pair of bearings 103 and 104. The shaft 102 is threaded between the two bearings and carries thereon a pulley 106

which is threaded for longitudinal movement on the shaft. The pulley 106 has a hub 107 provided with a groove 108 within which rides the arms 109 of a yoke which forms one end of a lever pivoted at 110 on the rheostat box. The other end of the lever is the rheostat arm 112 adapted to sweep over the contacts of the rheostat R₂. This rheostat R₂ is connected into the electrical system as shown in Fig. 4. The pulley 106 has a belt 115 driven by the small pulley 116 on the shaft of one of the driving drums 26. The ratio of the diameters of the pulleys in this construction is such that when the surface speeds of the reference roll 50 and the driving drum 26 are the same, then the pulley 106 will rotate with the shaft 102 and not travel longitudinally thereof. But if the motor driving the drum 26 should lag or run too fast, then the pulley 106 will be rotated at a different rate from that of pulley 101 and so will thread its way along the shaft 102 and carry with it the yoke 109 and swing the rheostat arm 112 over the contacts of the resistance and thus vary the current flow to the shunt field of the motor 30 and change its speed as required. Various other equivalent mechanical constructions may be employed in place of these two differential units of Figs. 2 and 3, which are so constructed and arranged that they will transmit any difference in speed of the two and bring the speed of the controlled motor back to synchronization with that of the reference roll 50 or its driving motor.

It will now be understood that the drums 36 for driving the back gray cloth may have their speeds controlled by similar mechanism, including a differential unit 120 (Fig. 1) which has one of its shafts 121 connected by a belt 122 with the reference roll 50 and its other shaft 124 connected by a belt 125 to a pulley on one of the drums 36. The intermediate shaft 127 of the differential unit is connected by a belt 128 with the pulley 129 of the rheostat R₃. The rheostat is so constructed and arranged that its rheostat arm 130 will remain in a neutral position when the shafts 121 and 124 are going at the same speed, but it will sweep over the contact points 132 in the proper direction to vary the speed of the motor 40 and bring it into synchronism with the reference roll 50 or its driving unit. The diameter ratios of the pulleys of this differential unit, as well as the unit for controlling the fabric drying drums, are such that when the drum driving motor moves the cloth at the same rate as it is moved by the printing machine, then the rheostat arm of the controlling rheostat unit will remain stationary in a middle position. The control of the speed of the back gray motor 40 is therefore accomplished in the same way as is the control of the speed of the other motor 30 and need not be further described.

I may use a steam engine or turbine or any suitable hydraulic, pneumatic or other type of motor for the prime mover. Also, I may use any such motor for the automatically controlled secondary motor, since the intermediate shaft of the differential apparatus may be connected to control finely a valve in a steam, air or hydraulic line or it may be connected to actuate other suitable types of control apparatus. I do not directly synchronize the two motor speeds, but I provide a structure wherein a speed reference unit is driven at a given desired rate and the speed of the controlled motor is coordinated with that unit. The reference unit is to be given a speed which is exactly the same as or is proportional

to the rate of movement of the fabric or the cloth or the blanket or other driven part at a point where the rate must be maintained uniform or regulated so as to insure a proper printing operation. Hence, the speed synchronization is controlled by the rate of that reference unit, which in turn moves at a rate determined by the speed of a prime mover and the controlled motors are thus lead by this prime mover through an intermediate agent moving at the speed imparted to one of the strips.

On the other hand, the control of speed is effected by direct control of the secondary motor and not through a variable speed transmission or other such apparatus. The control should be direct so as to avoid the introduction of uncertain variables into the control system. While the operations of some portions of the textile handling apparatus may be controlled in accordance with variable conditions in the system, such as a variable tension in the cloth or fabric, and the speeds of certain motors may be adjusted after such variation in tension or the like has occurred; yet that type of control does not satisfy the requirements of this invention, since a uniform tension and other conditions needed for the printing operation are not maintained where there must be variation in such a characteristic before it can effect a correction in the control system. The purpose of the speed control mechanism herein claimed is to minimize variation and not to let it build up far enough to actuate a control device. If variation in speed occurs even to a slight degree, the speed is automatically brought back to a condition of no variation, and this is accomplished before that slight increment of speed variation can effect the tension of the cloth or fabric materially. Other advantageous characteristics and requirements will now be apparent to one skilled in this art.

Many types of mechanical and electrical apparatus may be substituted for those above described or employed therewith to improve the working of the apparatus or to modify its operation in accordance with the requirements of a given installation. It will also be understood that various other motors of the printing apparatus may be synchronized with the reference unit in the manner above described. Suitable starting and other mechanism may be incorporated in the system as desired so that the several motors may be brought up to full speed from a stationary condition or regulated as desired. Also, selector switch mechanism may be employed to give desired speed for the printer roll, so that a given peripheral speed may be obtained after a different sized print roll has been installed in the machine. Switches and other control units may be used to insure both synchronization as above disclosed and separate and independent operation of the different power units, as may be required at times, such as when the printing step has been finished and it is desired to run the remaining fabric or cloth through the drying zone.

It will now be appreciated that the drawings and the above description are to be considered as illustrative of the general principles of this invention and a preferred embodiment of constructional details and not as limitations on the claims appended hereto.

I claim:

1. In combination with a cloth printing machine having at least a printing cylinder driven by an engraving roll of indeterminate diameter

and a second roll spaced from the printing cylinder upon which the cloth passes, a first electric motor for driving the engraving roll and the printing cylinder, a second electric motor for driving the said second roll, and means governed in response to the lineal speed of the said second roll and to the lineal speed of the cloth in the printing machine for varying the speed of one of said electric motors and causing both of said motors to move the cloth at substantially the same speed.

2. In combination, with a printing machine having at least a printing cylinder driven by an engraving roll of indeterminate diameter and a device spaced from the printing cylinder and bearing a direct relation to the speed of the cloth, a first electric motor for driving the said device, a second electric motor for driving the engraving roll and the printing cylinder, and speed control means responsive to the linear speed of both the cloth in the printing machine and in the said device for making one of said electric motors function as a governed motor to keep the linear speed of the cloth in the printing machine and the linear speed of the cloth in said device in synchrony.

3. A textile printing apparatus comprising a printing machine having a printing roll of indeterminate size, power mechanism including a motor for driving said roll and causing it to move cloth through the printing zone at a rate determined by the roll size, power mechanism including an independent motor for moving the cloth at a point remote from the printing zone, a speed reference unit independent of either motor which moves in an invariable speed ratio relative to the speed of the cloth in the printing zone as caused by said roll, a speed control device for controlling one of said motors and automatically actuated mechanism governed by said unit which operates said speed control device and causes the controlled motor to move the cloth as substantially the same rate as that at which it is moved by the other motor, so that the cloth is held under a substantially uniform tension at said remote point.

4. A textile printing apparatus comprising a printing machine having a printing roll of indeterminate size, associated mechanism including a motor for driving said roll and causing it to move a strip of cloth and a second strip of textile material through the printing zone at a rate determined by the roll size, means including a motor and associated mechanism for moving said second strip at a point remote from the printing zone, a speed reference unit independent of either motor which moves in an invariable speed ratio relative to the speed of one of said strips as caused by the printing roll, differential speed mechanism having a part movable in timed relation with said unit and another part movable in timed relation with said second strip at said remote point, and control mechanism operated by a variation in the relative speeds of said parts which controls one of said motors and causes the second strip to move at substantially the same rate as the cloth moves through the printing zone.

5. A textile printing apparatus comprising a printing machine having a printing roll of indeterminate size, master power mechanism including a motor for driving said roll and causing it to move cloth through the printing zone at a rate determined by the roll size, power mechanism including a secondary independent

motor for moving the cloth at a controlled rate at a point remote from the printing zone, a speed reference unit independent of either motor which moves in an invariable speed ratio relative to the speed of the cloth in the printing zone as caused by said roll, a speed control device for the secondary motor and mechanism automatically governed by said unit which controls said speed control device and causes the secondary motor to move the cloth at substantially the same rate as that at which it moves through the printing zone so that the cloth is held under a substantially uniform tension at said remote point.

10 6. A textile printing apparatus comprising a printing machine having a printing roll of indeterminate size, associated mechanism including a motor for driving said roll and causing it to move cloth through the printing zone at a rate determined by the roll size, a rotatable drying drum for drying and moving the cloth, power mechanism including an independent motor for rotating the drum, mechanism for varying the speed of one motor, speed control mechanism for the other motor, a speed reference unit which moves in an invariable speed ratio relative to the cloth movement in the printing zone as caused by said roll and means associated with said unit which controls said speed control mechanism and causes the two motors to move the cloth always at substantially the same speed through the printing zone and over the drying drum and to hold the cloth under a substantially uniform tension between the printing zone and the drying drum.

15 7. A textile printing apparatus comprising a printing machine having a printing roll of indeterminate size, associated mechanism including a primary motor for driving said roll and causing it to move cloth through the printing zone at a uniform rate determined by the roll size, power mechanism including an independent, governed motor for moving the cloth at a controlled and a uniform rate at a driving point remote from the printing zone, a speed reference unit independent of either motor which moves in an invariable speed ratio relative to the speed of the cloth in the printing zone as caused by the printing roll, differential mechanism having a part movable in a timed relation with said unit and another part movable in a timed relation with the cloth as moved by the governed motor, and speed control mechanism for varying the rate of the governed motor which is operated by a variation in the relative speeds of said parts and causes the governed motor to move the cloth at substantially the rate at which it moves through the printing zone.

20 8. A textile printing apparatus comprising a printing machine having a printing roll of indeterminate size, associated mechanism including a motor for driving said roll and causing it to move a strip of cloth and a second strip of textile material through the printing zone at a rate determined by the roll size, means including a governed motor and associated mechanism for moving said second strip at a point remote from the printing zone, a speed reference unit independent of either motor which moves in an invariable speed ratio relative to the speed of said cloth as caused by the printing roll, differential speed mechanism having a part movable in timed relation with said unit and another part movable in timed relation with said second strip, and con-

25 9. A textile printing apparatus comprising a printing machine having a printing roll of indeterminate size, associated mechanism including a motor for driving said roll and causing it to move cloth through the printing zone at a rate determined by the roll size, power mechanism including a secondary independent motor for moving the cloth at a controlled rate at a point remote from the printing zone, a speed reference unit independent of either motor which moves in an invariable speed ratio relative to the speed of said cloth as caused by the printing roll, differential speed mechanism having a part movable in timed relation with said unit and another part movable in timed relation with said second strip, and con-

trol mechanism operated by a variation in the relative speeds of said parts which controls said governed motor and causes it to move the second strip at substantially the same rate as the cloth moves through the printing zone.

9. A textile printing apparatus comprising a printing machine having a printing roll of indeterminate size, associated mechanism including a motor for driving said roll and causing it to move fabric to be printed and a back gray cloth through the printing zone at a speed determined by the roll size, means including two governed motors for moving said fabric and said cloth at two points remote from the printing zone, a speed reference unit which moves in an invariable speed ratio relative to the speed of the fabric as caused by said printing roll, and mechanism automatically controlled by said unit which causes the governed motors to move the fabric and cloth at said points at substantially the same rate as that of the fabric in the printing zone and thereby

maintaining the fabric and cloth under substantially uniform tensions.

10. A textile printing apparatus comprising a printing machine having a printing roll of indeterminate size, associated mechanism including a motor for driving said roll and causing it to move fabric to be printed and a back gray cloth through the printing zone at a speed determined by the roll size, a drum for drying the fabric, a drum for drying the cloth, two governed motors for rotating said drums and moving the fabric and cloth away from the printing zone, a speed reference unit which moves in an invariable speed ratio relative to the speed of the fabric as caused by said printing roll, and mechanism automatically controlled by said unit which causes the governed motors to move the fabric and cloth at substantially the same rate as that of the fabric in the printing zone and thereby maintaining the fabric and the cloth under substantially uniform tensions.

HERMAN A. SMITH.
